UNITED STATES PATENT OFFICE

2,116,385

ELASTIC FLUID GOVERNING MECHANISM

Robert H. Collingham, Rugby, England, assignor
to General Electric Company, a corporation of
New York

Application December 15, 1936, Serial No. 116,026
In Great Britain December 17, 1935

1 Claim. (Cl. 137—158)

The present invention relates to elastic fluid turbine governing mechanisms, more specifically to the kind of governing mechanisms which control the inlet valve of the turbine in response to changes in the vacuum of the turbine condenser. Such arrangements are important in order to prevent excessive blowing-off from the boilers in case it is necessary to disconnect the turbine from the boiler during failure of the vacuum.

10 The object of my invention is to provide an improved construction and arrangement for automatically controlling the flow of elastic fluid to turbines in response to pressure changes in the exhaust, that is, in response to changes of the 15 vacuum in the condenser of such turbines.

This is accomplished in accordance with my invention by the provision of an improved pilot valve arrangement for controlling the flow of actuating fluid to a servo-motor for moving the admission valve. The pilot valve according to 20 my invention has an element which is controlled in response to changes in vacuum in the condenser to effect closing of the turbine inlet valve as the vacuum in the condenser drops, and vice-versa.

25 For a better understanding of what I believe to be novel and my invention, attention is directed to the following description and the claim appended thereto in connection with the accompanying drawing which illustrates an embodiment of a preferred arrangement of my invention.

The arrangement shown in the drawing comprises an elastic fluid turbine 10 which has an inlet valve 11 for controlling the flow of elastic fluid thereto. The exhaust of the turbine is condensed in a condenser 12. The valve 11 is moved by means of a servo-motor 13 to which actuating fluid such as oil is supplied by a pilot valve 14 connected to the servo-motor 13 by a conduit 15. The pilot valve 14 has a movable valve member 16 disposed within a sleeve or bushing 17, which latter has a number of ports 18 and is movably disposed within a cylinder or casing 19. Actuating fluid for operating the servo-motor or motors 40 45 50 55

13 is conducted to the pilot valve through port 20 and discharged therefrom through a port 21. The sleeve 17 and the lower portion of the casing 19 form a chamber 22 to which oil or like actuating fluid under pressure is conducted to effect movement of the sleeve. The flow of actuating fluid to the chamber 22 and the discharge of fluid therefrom is controlled by an auxiliary pilot valve 23 which has a casing 24 attached to the casing 19 and a movable valve member 25 with a stem 55 connected to an intermediate point of a lever 26.

The right-hand end of the lever 26 is pivoted to a bellows 27 and the left-hand end of the lever 26 is connected by follow-up means including a link 28 and a forked member 28a to the sleeve 17. The bellows 27 communicates with the condenser 12 through a pipe 29. The pressure in the bellows is counteracted by means of an adjustable spring 30.

During normal vacuum condition the bellows 27 is in its maximum depressed condition and 10 the pilot valve head 25 of the auxiliary pilot valve is in its bottom position so that no force is exerted by oil pressure on the bottom of the sleeve 17. The latter then is held in its bottom position by 15 the action of a spring 31. The pilot valve 16 may be normally controlled by a speed governor 31a connected to the valve 16 and the motor 13 by 20 a follow-up lever 31b. With this arrangement an increase in speed causes downward movement of the left-hand end of the floating lever 31b and consequently downward movement of the valve member 16 whereby communication is established 25 between the inlet port 20 and the conduit 15, permitting the supply of actuating fluid to the hydraulic motor 13 and resulting in closing movement of the turbine inlet valve 11. Similarly, a 30 drop in speed causes opening movement of the valve 11. As long as the sleeve 17 is in its lower position, the governor 31a for normally controlling the flow of elastic fluid to the turbine can 35 effect complete opening of the admission valve 11. If now for some reason the vacuum falls below a predetermined value fixed by the tension of the spring 30, the bellows is expanded and thereby causes upward or opening movement of the auxiliary pilot valve 25 until actuating fluid under 40 pressure is admitted to the chamber 22. This causes upward movement of the sleeve 17 until the follow-up mechanism between the sleeve 17 and valve member 25 restores the auxiliary pilot 45 valve to its normal neutral position. Upward movement of the sleeve 17 establishes connection between the port 20 and the conduit 15 and thus permits the flow of actuating fluid to the lower part of the hydraulic cylinder 13. This effects 50 upward movement of the piston of the servo-motor 13, resulting in closing movement of the inlet valve 11 and consequently a decreased flow of elastic fluid to the turbine 10. The closing movement of the inlet valve 11 is automatically 55 effected without any change in the main governor setting, not shown, and the portion of the load thrown off by the setting may be transferred to other turbines operating in parallel.

If the vacuum drops further, the operation de- 55

- scribed above is repeated until the turbine is carrying such a load that any further reduction might cause dangerous heating of the low pressure end of the turbine. Preferably, therefore, 5 the vacuum trip is set to operate automatically to effect shutting off of the steam supply at this load. Actuating fluid leaking along the outer surface of the sleeve is discharged through an opening 33 into a channel 34.
- 10 With my above invention I have accomplished an improved construction and arrangement of governing mechanism for elastic fluid turbines, especially useful in connection with arrangements where a plurality of turbo-alternators are connected 15 to the same electrical system. My improved arrangement permits the reduction of the load of any particular turbo-alternator with infinite fineness of graduation.
- 15 What I claim as new and desire to secure by 20 Letters Patent of the United States is:
- An elastic fluid turbine arrangement including

the combination of a turbine having an inlet valve for controlling the flow of actuating fluid thereto, a condenser for condensing elastic fluid exhausted from the turbine, and means for positioning the inlet valve in response to changes in vacuum in 5 the condenser, said means comprising a servomotor for moving the valve, a pilot valve for the servomotor, the pilot valve including a valve member, a sleeve forming ports and surrounding the valve member and a stationary casing surrounding the sleeve, the sleeve and the stationary casing forming a chamber, means for controlling the flow of actuating fluid to the chamber in response to changes in vacuum in the condenser to effect movement of the sleeve, said means comprising an auxiliary pilot valve, a device responsive to changes in vacuum for moving the auxiliary pilot valve and a follow-up mechanism connected between the auxiliary pilot valve and the sleeve.

ROBERT H. COLLINGHAM.
